UNITED STATES PATENT OFFICE.

HAROLD SOMERS, OF BROOKLYN, NEW YORK.

DESIGN FOR A FLY-KILLING DEVICE.

44,549.

Specification for Design.

Patented Aug. 19, 1913.

Application filed January 19, 1912. Serial No. 672,212. Term of patent 14 years.

To all whom it may concern:

Be it known that I, HAROLD SOMERS, a citizen of the United States, residing at Brooklyn, in the county of Kings and State of New York, have invented a new, original, and ornamental Design for Fly-Killing Devices, of which the following is a specification, reference being had to the accompanying drawings, forming a part thereof, in which—

Figure 1 is a perspective view of a fly killing device, showing my design, and Fig. 2 is a side elevation thereof.

I claim:

The ornamental design for a fly killing device, as shown.

HAROLD SOMERS.

Witnesses:

THOS. SMITH,
ANDREW J. RYDER.
